PAPER ROLL DISPENSER

Frank Jacomare, Chicago, Ill.

Application October 22, 1954, Serial No. 463,895

9 Claims. (Cl. 242—55.3)

This invention relates generally to cabinet construction for holding rolls of paper wherein paper may be readily dispensed from a roll and to means associated with the cabinet for holding an auxiliary or reserve supply of paper rolls.

A primary object of this invention is to provide improvements in paper roll dispensers wherein while the expended roll of paper may be easily removed from the cabinet, at the same time means is provided whereby the mechanism is temporarily urged during dispensing operation to a position wherein a newly placed roll may not be accidentally displaced or removed from the cabinet.

Another object of this invention is to provide improvements in paper roll dispensing cabinets wherein a supply of roll paper is held in reserve above the normal supply, means being provided for holding the reserve supply in elevated position until such time as it is needed.

These, together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a vertical section taken through the improved dispenser;

Figure 2 is a horizontal section taken substantially along the plane of section line 2—2 of Figure 1;

Figure 3 is a vertical section taken substantially along the plane of section line 3—3 of Figure 1;

Figure 4 is an enlarged vertical section taken substantially along the plane of section line 4—4 of Figure 1;

Figure 5 is an enlarged sectional view showing the plunger mechanism;

Figure 6 is a vertical section similar to Figure 1 but showing the modified form of construction;

Figure 7 is a horizontal sectional view taken through the shock absorbing mechanism of the construction shown in Figure 6 for illustrating a modified link structure; and

Figure 8 is a transverse sectional view taken substantially upon the plane of section line 8—8 in Figure 7.

Referring now more particularly to the drawings, and at this point most specifically to Figures 1—3, the reference numeral 10 indicates the cabinet construction generally which will be seen to consist of a front wall 12, a rear wall 14, a removable cover member 16 and opposite side wall members 18 and 20. The entire assemblage may be removably secured to a suitable support member such as a wall 22 by means of fasteners 24 which extend through the rear wall 14 in the manner shown most clearly in Figure 1.

It is to be noted that the front and rear edges at the lower ends of the side walls 18 and 20 are cut away as at 26 and 28 to permit ready access to a roll of paper 30 disposed between the lower ends of these side walls in the manner shown. The paper rolls are of entirely conventional construction and consist of inner rolls or cores 32

upon which the paper is wound and a spindle 36 which projects through the core 32 and extends on opposite sides thereof for the purpose of rotatably supporting the paper rolls.

- 5 The manner in which the paper rolls are supported in the cabinet structure 10 will be seen most clearly from a study of the Figures 1—3 wherein it is to be noted that a horizontal support arm 38 is pivotally secured intermediate its ends to each of the side walls 18 and 20 as by 10 pivot pin member 40. These support arm members are grooved or notched as at 42 to receive the opposite end portions of the spindle 36 such that the paper rolls are rotatably supported in the proper manner. In order to maintain the arms 38 in a substantially horizontal position, links 44 are pivotally secured at their lower ends to the support arms 38 by a pin member 46 and the upper ends of these links terminate in plunger mechanisms bearing against the undersurface and in a notch of a horizontal actuator shaft 47 associated with each arm 38.
- 15 The link members are adjustable in length by virtue of their threaded end portions 48 which receive the clevis members 50 whose bifurcated lower ends or ears 52 receive the arms 38 therebetween and are pivotally connected thereto.
- 20 A pair of track members 60 and 62 are rigidly secured in spaced parallelism to each of the side walls 18 and 20, the position of these guide or track members being such that the space therebetween is substantially in vertical registry with the notches 42 in the support arms 38.
- 25 These track or guide members terminate at their upper ends adjacent the cover member 16 and are adapted to guidedly receive therebetween the end portions of spindles 36.
- 30 For the purpose of holding a roll of paper in reserve above the dispensing roller which is disposed between the lower end portions of the side walls 18 and 20, the horizontal actuator arm 47 will be seen to project through a bushing 63 in one of the track members 60 and to terminate at a point closely adjacent the other track member 40 in a manner illustrated most clearly in Figure 1. Thus, the inner ends of the actuator arm 47 provide a support on which the uppermost roll of paper is placed.
- 35 At its outer end, the actuator rod or shaft 47 is provided with a pull button 64 secured thereto as by nut members 66 and the inner end portion of the outer end of the shaft is provided with a stub collar 68 to limit its inward sliding motion with respect to the track members 60. A coil spring 70 surrounds the shaft between the front wall 12 and the tracks 60 and bears against a collar member 72 rigid with the shaft such that when the shaft is retracted, the spring 70 will be loaded to normally return the shaft to the position shown in Figure 1. As previously mentioned, the upper end of the links 44 are provided with 40 plunger mechanisms which are illustrated most clearly in Figure 5. The uppermost ends of the links 44 are threaded as at 73 and engaged thereon are the thimble members 80 in which the pistons 82 of the plunger rods 84 are slidable. Disposed below the piston 82 and the upper end of the links is a compression spring 86. The plunger is provided at its upper end with an enlarged head portion 88 received in a groove or notch 90 in the actuator shafts 47 and it will thus be readily apparent that the actuator shafts are normally held in their inwardly projected positions, and the enlarged head 88 and the notch 90 may be such as to positively prevent withdrawal of the plungers at any time that interengagement may be had therebetween.
- 45 During such time as a roll is disposed on the support arms 38, the arms will be swung downwardly about their pivots 40 in the position shown in Figure 1. However, when the roll of paper on the spindle has been depleted,

70

and the spindle has been removed from the support arms 38, the support arms will be overbalanced by the weight of the links and associated mechanisms such that the inner ends 91 of the arms will swing upwardly to engage the lower beveled end 92 of the rearmost track or guide member 62. Simultaneously, this movement of the support arms will have retracted the enlarged head 88 from the notches 90 in the actuator shafts 47, permitting the handle 64 to be grasped so as to retract or withdraw the actuator shafts. The purpose of this construction is such as to preclude accidental disengagement of the spindle 36 of the next paper roll which is automatically dropped as the actuator shafts 47 are retracted, that is, the rearmost end of the arms 38 are normally disposed with respect to the lower ends of the track members 62 such that a spindle may be disengaged therefrom by moving it rearwardly. However, when the rearward ends of the arms are outwardly swung, insufficient space is left to permit the spindle 36 from being disengaged.

The spring 86 does, however, act as a shock absorber as the uppermost roll of paper is dropped thereon. To further aid in absorbing the shock as the uppermost roll of paper is dropped, a yoke 100 is provided. This yoke is secured at its lower end to the links 44 and extends upwardly around on opposite sides of the shafts 47 for connection to a rod 102 which projects into the cylinder member 104 and has secured at its uppermost end a resilient piston assembly 106 in a manner shown most clearly in Figure 4. The upper end of the cylinder 104 is provided with a bleed passage 108 and a screw valve 110 associated therewith such as to guide the rapidity with which the piston 106 may be moved upwardly in the cylinder. The cylinder is held by a collar or sleeve 112 and an associated set screw 114 for initially adjusting the position of the cylinder.

Referring now more particularly to Figures 6-8 wherein the modified form of the invention is shown, it will be seen that the cabinet 120 in this case is recessed into the wall structure 122, it being appreciated that the cabinet may be disposed flush therewith as desired. The cabinet 120 consists of a front wall 124, a rear wall 126, a bottom wall 128, a top wall 130 with the lower portion of the front wall being open and the side walls notched away as at 132 to permit access to the roll and with the top portion of the front wall being open and having associated therewith a hinged cover member 134 in the manner shown. The cover may be provided with a knob 136 which is rotatable and has attached to its inner end a lateral projecting latch member 138 so that rotation of the knob will effect latching of the cover or door member.

Like the modification shown in Figure 1, the cabinet assembly 120 is provided with guide members 140 and 142, the former of which is angularly offset as at 144 such that a paper roll may be disposed thereon in the manner shown in dotted lines.

The actuator shaft 146, the support arms 148 and the links 150 with the exception that the yoke members 100 previously described and their associated cylinder and piston assemblies are omitted, are identical to those previously described.

In the case of the modifications shown in Figures 6-8, the shock absorber assemblage incorporates a star wheel mechanism indicated generally by the reference character 160.

The shock absorber mechanism consists of a pair of star wheel members mounted on a common shaft 162 and connected together by any suitable means such as a plurality of rods 164 extending therebetween which form abutment means against which a spring 166 engages. The spring 166 is of cantilever construction and is intended to resist the rotation of the star wheel assemblage, it being noted that one finger or point 168 of the star wheels are always projected between the track members 140 and 142 such as to catch the spindle ends of the paper roll as it is dropped during the dispensing operation.

Referring now more particularly to Figures 7 and 8 wherein a still further modified construction is shown, the modification consists of a departure in structure of the link assemblage such as those illustrated by the reference characters 44 and 150 and in this case a link is formed of two separate shaft members or rods 170 and 172, the lower of which is pivotally connected to the support arms and the upper of which is disposed in abutting engagement with the lower notched first portion of the actuator shafts. Each link portion 170 and 172 has a collar 174 or 176 rigidly attached thereto and one of the collars has rigidly secured in depending fashion thereto a plurality of plunger or rod members 178 which slidably project through the other collar member in the manner illustrated most clearly in Figure 7. The adjacent ends of the shaft portions 170 and 172 are disposed in spaced relation and a coil spring 180 is disposed between the two collars 174 and 176 to normally maintain in the spaced apart relation shown.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly, all suitable modifications and equivalents may be resorted to, falling within the scope of the appended claims.

What is claimed as new is as follows:

- 30 1. A paper roll holder comprising a cabinet including a front wall, a rear wall, opposite side walls and having an open bottom, vertical track members secured to said side walls and adapted to guidably receive opposite ends of a paper roll spindle, a pair of horizontal support arms pivotally secured intermediate their ends to said side walls, each of said support arms having one end portion underlying a corresponding track member, a pair of horizontal actuator shafts slidably received in said front wall, each of said shafts having an inner end portion projecting into a corresponding track member to support a reserve paper roll, a vertical link pivotally secured to the other end of each of said support arms, a spring loaded plunger carried at the upper end of each link and engaged against a corresponding actuator shaft.
- 35 2. A paper roll dispenser comprising a cabinet including a front wall and opposite side walls and having an open bottom portion, pairs of vertical guide members secured to said side walls, a support arm pivotally secured to each side wall intermediate its ends and having one end underlying corresponding guide members, actuator shafts slidably received in said front wall and projecting through one of each pair of guide members to a point closely adjacent the other, links pivotally connected to the other ends of said support arms and releasably engaged at their upper ends in recesses in said actuator shafts, whereby retraction of said shafts will permit said support arms to swing toward the lower ends of said guide members.
- 40 3. A paper roll holder comprising a cabinet including a front wall, a rear wall, opposite side walls and having an open bottom, vertical track members secured to said walls and adapted to guidably receive opposite ends of a paper roll spindle, a pair of horizontal support arms pivotally secured intermediate their ends to said side walls, each of said support arms having one end portion underlying a corresponding track member, a pair of horizontal actuator shafts slidably received in said front wall, each of said shafts having an inner end portion projecting into a corresponding track member to support a reserve paper roll, a vertical link pivotally secured to the other end of each of said support arms, a spring loaded plunger carried at the upper end of each link and engaged against a corresponding actuator shaft, and shock absorbing means connected with said links.
- 45 4. A paper roll dispenser comprising a cabinet includ-

ing a front wall and opposite side walls and having an open bottom portion, pairs of vertical guide members secured to said side walls, a support arm pivotally secured to each side wall intermediate its ends and having one end underlying corresponding guide members, actuator shafts slidably received in said front wall and projecting through one of each pair of guide members to a point closely adjacent the other, links pivotally connected to the other ends of said support arms and releasably engaged at their upper ends in recesses in said actuator shafts, whereby retraction of said shafts will permit said support arms to swing toward the lower ends of said guide members, and shock absorbing means connected with said links.

5. A paper roll holder comprising a cabinet including a front wall, a rear wall, opposite side walls and having an open bottom, vertical track members secured to said side walls and adapted to guidably receive opposite ends of a paper roll spindle, a pair of horizontal support arms pivotally secured intermediate their ends to said side walls, each of said support arms having one end portion underlying a corresponding track member, a pair of horizontal actuator shafts slidably received in said front wall, each of said shafts having an inner end portion projecting into a corresponding track member to support a reserve paper roll, a vertical link pivotally secured to the other end of each of said support arms, a spring loaded plunger carried at the upper end of each link and engaged against a corresponding actuator shaft, a cylinder secured to each side wall, a piston, slideable in each cylinder, connected with each link, and an air bleed passage in each cylinder.

6. A paper roll dispenser comprising a cabinet including a front wall and opposite side walls and having an open bottom portion, pairs of vertical guide members secured to said side walls, a support arm pivotally secured to each side wall intermediate its ends and having one end underlying corresponding guide members, actuator shafts slidably received in said front wall and projecting through one of each pair of guide members to a point closely adjacent the other, links pivotally connected to the other ends of said support arms and releasably engaged at their upper ends in recesses in said actuator shafts, whereby retraction of said shafts will permit said support arms to swing toward the lower ends of said guide members, a cylinder secured to each side wall, a piston, slideable in each cylinder, connected with each link, and an air bleed passage in each cylinder.

7. A paper roll holder comprising a cabinet including a front wall, a rear wall, opposite side walls and having an open bottom, vertical track members secured to said side walls and adapted to guidably receive opposite ends of a paper roll spindle, a pair of horizontal support arms

- pivotally secured intermediate their ends to said side walls, each of said support arms having one end portion underlying a corresponding track member, a pair of horizontal actuator shafts slidably received in said front wall, each of said shafts having an inner end portion projecting into a corresponding track member to support a reserve paper roll, a vertical link pivotally secured to the other end of each of said support arms, a spring loaded plunger carried at the upper end of each link and engaged against a corresponding actuator shaft, and a shock absorbing means associated with said track members, said shock absorbing means including a star wheel rotatably mounted adjacent said track members, and means for resisting rotation of said star wheel.
15. 8. A paper roll dispenser comprising a cabinet including a front wall and opposite side walls and having an open bottom portion, pairs of vertical guide members secured to said side walls, a support arm pivotally secured to each side wall intermediate its ends and having one end underlying corresponding guide members, actuator shafts slidably received in said front wall and projecting through one of each pair of guide members to a point closely adjacent the other, links pivotally connected to the other ends of said support arms and releasably engaged at their upper ends in recesses in said actuator shafts, whereby retraction of said shafts will permit said support arms to swing toward the lower ends of said guide members, and a shock absorbing means associated with said track members, said shock absorbing means including a star wheel rotatably mounted adjacent said track members, and means for resisting rotation of said star wheel.
20. 9. A paper roll holder comprising an enclosure having an open bottom and opposite side walls, vertical guide means on each side wall and adapted to guidably receive opposite ends of a paper roll spindle, a pair of horizontal support arms pivotally secured to said side walls, each of said support arms having a portion underlying a corresponding guide means, a pair of horizontal actuator
25. 40. 45. shafts slidably mounted in said cabinet, each of said shafts having an inner end portion projecting into a corresponding guide means to support a reserve paper roll, a link extending between each of said support arms and a corresponding actuator shaft for locking the shafts against movement while a paper roll is carried by the support arms.
